J. G. LEHMAN,
TEMPERATURE CONTROL OF KETTLES BY ZONES,
APPLICATION FILED SEPT. 27, 1919.

1,407,666.

Patented Feb. 21, 1922.

UNITED STATES PATENT OFFICE.

JOHN GEORGE LEHMAN, OF BETHLEHEM, PENNSYLVANIA, ASSIGNOR TO BETHLEHEM FOUNDRY & MANUFACTURING COMPANY, OF BETHLEHEM, PENNSYLVANIA, A CORPORATION OF PENNSYLVANIA.

TEMPERATURE CONTROL OF KETTLES BY ZONES.

REISSUED

1,407,666.

Specification of Letters Patent. Patented Feb. 21, 1922.

Application filed September 27, 1919. Serial No. 327,007.

To all whom it may concern:

Be it known that I, JOHN GEORGE LEHMAN, a citizen of the United States, residing at 244 E. Market Street, Bethlehem, in the county of Northampton and State of Pennsylvania, have invented a certain new and useful Temperature Control of Kettles by Zones, of which the following is a specification.

10 My invention relates to the heating or cooling of the walls of kettles and other receptacles, intended for the heat-treatment of liquids, particularly in carrying out chemical processes.

15 The purpose of my invention is to provide for different applications of heating or cooling fluid throughout different layers, belts or zones of a kettle.

20 A further purpose is to provide for heating one part of a liquid under treatment, at the same time that the heat is withdrawn from another part, or that the other part thereof is cooled, so as to give differential temperatures to the several parts thereof.

25 Further purposes will appear in the specification and in the claims.

I have preferred to illustrate my invention by but one general form, selecting a form which is practical, efficient and inexpensive and which at the same time well illustrates the principles of my invention.

30 Figure 1 is a horizontal section showing one arrangement of connections for the practice of my invention.

35 Figure 2 is a vertical broken section taken upon line 2—2 of Figure 1.

Figure 3 is a broken vertical section upon line 3—3 of Figure 1.

40 Figure 4 is a horizontal section showing a second arrangement of connections.

Figure 5 is a broken vertical section upon line 5—5 in Figure 4.

In the drawings, similar numerals indicate like parts.

45 In many different lines of manufacture where heat-treatment of liquids is required, it is desirable to have the heat of the liquid under complete control, and my invention is directed to rapid, simple and effective control, differentiating between different layers or levels of the liquid being treated.

50 The container 6, generically called a kettle, is provided with a plurality of passages,

or, preferably a continuous passage within its walls, shown as pipes 7, in order that a 55 fluid may be passed through them for the purpose of heating or cooling the walls of the kettle, and thus correspondingly heating or cooling the contents.

These several passages 7 have been arranged in groups or in belts of which I show three, at 8, 9 and 10, with separate inlets and outlets, if separate sections be used, as in Figures 1—3, or tapped at intervals to provide inlets and outlets, where the passage 65 is continuous, as in Figures 4 and 5.

In the form shown in Figures 1—3, these belts have separate inlets 11, 12 and 13, each from either of two different sources of supply and each source valved at 14 to control 70 the supply. The one general source of supply 15 is available for any of the three inlets. The other sources, 16, 17 and 18 are separate, thus providing for different temperatures of heated or superheated steam, cold water, etc. 75 In this form there are separate outlets also, at 19, 20 and 21, valved at 14 and connecting with a main discharge pipe 22; so that any one of the single belts may be heated or cooled without affecting the temperature accessible in another or others of the belts of the set.

In the form shown in Figures 4 and 5 there are three general sources of fluid supply, at 15', 15² and 15³, each available for any of the 85 inlets and cut-off from them by valves 14, but only one outlet for the three belts, necessitating the use of the lower belt, in connection with the second or middle belt and both the lower and middle belts in conjunction 90 with the top belt, where fluid is applied. As it is desirable, almost invariably to heat the lower part of the contents, whether the upper part is being heated or not, the single outlet form is ordinarily not objectionable, 95 and the additional outlets of Figure 3, are not ordinarily necessary.

The general sources of supply can be suited in number and character to the needs of the particular installation, with or without 100 separate outlets.

When the kettle has been filled with the liquid to be treated, heating or cooling fluids can be supplied to any of the belts desired, together or with different temperatures in 105 adjoining belts, giving great flexibility to

the application of the heat-treating and cooling fluids.

Having thus described my invention, what I claim as new and desire to secure by Letters Patent is:

1. In a device for treating liquids, a kettle having fluid passages in the walls thereof, and a plurality of points of inlet to and outlet from the said passages, in combination 10 with controlled fluid supply for the inlets whereby fluid can be passed through the passages surrounding one or more belts or zones of said kettle without passing through the other belt or belts thereof.
- 15 2. In a device for treating liquids, a kettle having spirally arranged piping in the walls thereof, surrounding several belts or zones of the kettle, in combination with separate inlets for the piping in each of said belts or 20 zones and outlet therefor, whereby different fluids can be applied at the same time in different belts or zones.
- 25 3. In a device for treating liquids, a kettle having a spirally arranged passage for fluid in the walls thereof, divided into belts having an inlet and outlet for the passage in

each belt, in combination with fluid supply for said inlets.

4. In a device for treating liquids, a kettle having a spirally arranged passage for fluid 30 in the walls thereof, divided into belts having an inlet and outlet for the passage in each belt, in combination with fluid supply for the same belt having different temperatures of supply. 35

5. In a device for treating liquids, a kettle having a spirally arranged passage for fluid in the walls thereof, divided into belts having an outlet for the passage in each belt, in combination with separate inlets to the passages for the different belts and a plurality of temperatures of supply fluid for each of 40 said inlets.

6. In a device for treating liquids, a kettle having spiral paths in its walls for fluid 45 passage, divided into belts having inlets and outlets for the passages in the different belts, in combination with fluid supply at different temperatures for the inlets and valve means for cutting out any inlet from any or all 50 supply.

JOHN GEORGE LEHMAN.
